WALTHALL RIDGWAY SMITH, OF NAPA, CALIFORNIA.

CAMERA ATTACHMENT.

SPECIFICATION forming part of Letters Patent No. 733,292, dated July 7, 1903.

Application filed December 15, 1902. Serial No. 135,271. (No model.)

To all whom it may concern:

Be it known that I, WALTHALL RIDGWAY SMITH, a citizen of the United States, and a resident of Napa, in the county of Napa and State of California, have invented a new and Improved Camera Attachment, of which the following is a full, clear, and exact description.

The object of this invention is to provide a hood which may be conveniently applied to a camera and used effectively to take the place of the usual focusing-cloth.

To this end the invention comprises certain novel features of construction which enable the attachment to be permanently connected with the camera and yet thrown into open position whenever it is desired to reach the interior of the camera for adjustment or other purposes.

This specification is a specific description of one form of the invention, while the claims define the actual scope thereof.

Reference is to be had to the accompanying drawings, forming a part of this specification, in which similar characters of reference indicate corresponding parts in both the figures.

Figure 1 is a side elevation with parts in section, and Fig. 2 is a perspective view showing the attachment in an open position.

The attachment comprises a main frame-section *a*, which is rectangular in form and adapted to fit firmly against the focusing end of the camera. This frame-section is provided with a beading *a'*, passing around its forward edge and adapted to engage the camera to make a light-tight connection.

*a*² indicates brackets which are fastened to said frame-section *a* and adapted to carry screws for connecting the frame-section with the camera. Connected by hinges *b'* (see dotted lines in Fig. 1) is a swinging frame-section *b*, which is rectangular to match accurately with the section *a* and which is adapted to engage a bead *c*, passing through the inner side of the frame-section *a* and projecting rearward beyond the edge thereof, this bead *c* forming a light-tight connection between the two frame-sections *a* and *b*. *b*² indicates a latch of any convenient form for removably holding the free end of the section *b* connected with this section *a*.

An accordion hood *d* is attached to the

frame-section *b* and tapers rearward, as illustrated, this hood carrying at its rear end a wall *e*, having an opening therein and around which extends a shade *f*. This shade is shaped to fit snugly against the face of the photographer, so that he may look through the hood without admitting light thereinto. For supporting the hood to move in and out and for holding it at the desired position I employ at each side thereof a lazy-tongs *g*, one end of each of which is connected with the section *b* and the other ends of which are connected with extensions *e'* of the end wall *e*. These lazy-tongs allow the hood to be contracted or extended at will, and said lazy-tongs are rendered rigid to hold the hood at the desired adjustment by means of guide-plates *h*. These plates are one for each lazy-tongs, and one end of each plate is pivotally connected to a pivot between two links of the tongs, said plate extending across the tongs and having its other end slotted, as indicated at *h'*, to receive the opposite pin 75 loosely therein.

*h*² indicates a thumb-nut for clamping the parts *h* and *g* rigidly together. It is clear that by this means the lazy-tongs may be locked rigidly in the desired adjustment. 80

In using the invention the brackets *a*² are fastened to the rear side of the camera, and after the camera has been properly adjusted the frame-section *b* is thrown to the closed position and held thereat by the latch *b*². The hood *d* is now adjusted, the extensions *e'* being orificed, as indicated at *e'*, thus furnishing convenient hand-holes for the photographer. In adjusting this hood the end wall *e* should be placed at proper focusing position, and when this has been effected the thumb-nuts *h*² should be tightened, thus rendering the tongs *g* rigid and preventing the hood *d* from moving out of the adjustment to which it has been placed. The photographing operation may now be carried on conveniently and without involving the many disadvantages of the well-known focusing-cloth. When the camera is not in use, the hood and its attached parts may be folded snugly 100 against the rear side thereof, and therefore they will not materially increase the size of the camera.

Various changes in the form, proportions,

and minor details of my invention may be resorted to without departing from the spirit and scope thereof. Hence I consider myself entitled to all such variations as may lie 5 within the scope of my claims.

Having thus described my invention, I claim as new and desire to secure by Letters Patent—

1. A camera attachment comprising a main 10 frame-section, a swinging frame-section hinged thereon, a latch for removably holding the swinging frame-section engaged with the main section, a hood carried on the swinging section, means for extending said hood to a 15 predetermined position, and means for locking the hood in said position.

2. A camera attachment comprising a main 20 frame-section, a swinging frame-section hinged thereon by vertically-disposed pivots, a latch for removably holding the swinging frame-section engaged with the main section, an extensible hood carried on the swinging section, expandible means for moving the hood into a desired position of extension, 25 means for locking the expandible means, and a bead extending around the main section and projecting from the rear edge thereof, said bead being adapted to be engaged by the swinging section to form a light-tight connection 30 between the hood.

3. A camera attachment comprising a main 35 frame-section, adapted to be fastened to the camera, a swinging frame-section hingedly mounted on the main frame-section, said sections meeting each other edge to edge, a bead mounted over the meeting edges of said sections to form a light-tight connection between them, an extensible hood attached to the swinging section, an end wall at the outer end

of the hood, and means connected with the 40 end wall and with the swinging frame to adjustably hold the hood.

4. A camera attachment comprising a frame-section, an extensible hood, an end wall at the outer end of the hood, said wall having an 45 opening therein to permit observation through the hood, lazy-tongs connecting the two ends of the hood, a slotted bar extending across the tongs and having sliding connection with one side thereof, and a set-screw 50 extending through said slot and engaging with a portion of the tongs for locking the latter against expansible movement.

5. A camera attachment comprising an extensible hood, means for mounting the same 55 on the camera, an end wall at the outer end of the hood, said wall having inner extensions forming hand-grips and a central opening forming an observation-opening through the hood, and means connected with the hand-holes adjustably to hold the hood.

6. A camera attachment comprising an extensible hood, means for mounting the same 65 on the camera, an end wall at the outer end of the hood, said wall having inner extensions forming hand-grips and a central opening forming an observation-opening through the hood, and means connected with the hand-holes adjustably to hold the hood, said means being in connection with the extensions of 70 the end wall and lying at one side of the hood.

In testimony whereof I have signed my name to this specification in the presence of two subscribing witnesses.

WALTHALL RIDGWAY SMITH.
